COLLAPSIBLE DISPLAY STAND

Claude C. Nuckols, Menands, N. Y.

Application March 30, 1931, Serial No. 526,489

2 Claims. (Cl. 211—156)

This invention provides a collapsible display stand which can be very easily and quickly set up for use, and the capacity of the stand varied as the occasion may require.

5 An important object of the invention resides in the provision of a collapsible display stand including a shelf adapted to be supported at any desired height within the stand, so that the merchandise receiving compartment can be varied 60 in size as may be desired.

One of the chief characteristics of the present invention resides in the provision of a novel construction of means for supporting the shelf at any desired height within the stand, and in a 15 manner to effectively add to the strength and rigidity of the entire structure as a unit.

In carrying out the invention I comprehend the provision of separable supporting elements for the shelf, which elements are adapted to be selectively inserted in slots in the body of the stand, to support the shelf at any desired height, and which elements can be readily and conveniently removed when it is desired to collapse the stand 20 for either storage or shipping purposes.

25 The nature and advantages of the invention will be better understood when the following detail description is read in connection with the accompanying drawings, the invention residing in the construction, combination and arrangement of parts as claimed.

30 In the drawings forming part of this application like numerals of reference indicate similar parts in the several views and wherein:

Figure 1 is a perspective view of one embodiment of the invention.

Figure 2 is a vertical sectional view.

Figure 3 is a top plan view with the shelf partly broken away.

Figure 4 is a view of the body of the stand collapsed.

40 Figure 5 is a view of one of the shelf supporting elements.

Figure 6 is a view similar to Figure 3 illustrating the use of an increased number of shelf supporting elements.

45 Figure 7 is a fragmentary sectional view through a modified form of the invention.

Figure 8 is a detail view showing a portion of the shelf and one of its supporting elements.

50 Referring to the drawings in detail 10 indicates the body of the display stand, which is formed from a single piece of any suitable material, preferably corrugated paper board. The free edges of the material are brought together and secured in any suitable manner, preferably by an

adhesive strip 11. The body 10 is herein shown octagonal in shape, but it can be of any cross sectional configuration without departing from the spirit of the invention. The stand is open at both ends and either end can be arranged 60 uppermost for use. Irrespective of the number of walls the body includes, depending on its cross sectional contour, the walls are connected by fold lines which permit the body 10 to be collapsed as shown in Figure 4. 65

The stand also includes a shelf 12 adapted to be positioned within the body 10, and of course corresponds in shape with the cross sectional configuration of the body. The shelf when positioned within the body engages the walls of the latter and therefore assists in holding the stand set up for use, in addition to increasing the strength and rigidity of the structure as a whole. The shelf can be supported at any desired height within the body 10, and thus vary the size of 70 the merchandise receiving compartment. In this way a large number of packages or articles can be arranged within the stand, out of view, and without in any way affecting the attractive display of uppermost packages or other merchandise supported by the shelf. In this connection, it will be further observed, that inasmuch as both ends of the stand are open, either end can be arranged uppermost for use. 75

80 In carrying the invention into effect, I employ a novel construction of means for supporting the shelf, and which means is capable of being readily associated with or separated from the body 10 as the occasion may require. In accordance with one embodiment of the invention I provide a 85

plurality of supporting elements 13 which are passed through aligned slots 14 in opposed walls of the body 10, and in crossed relation as clearly illustrated. While these elements 13 can be of any suitable character and connected to the adjacent walls of the body 10, they are preferably 90 flat metal strips, each having one end normally bent at a right angle as at 15. The opposite normally straight end is adapted to be passed through the aligned slots of the opposed walls,

95 until the right angular end portion 15 engages its adjacent wall, after which the opposed end of said element is also bent at a right angle against its adjacent wall as at 16. The shelf reposes on these supporting elements and only two of such 100 elements are usually enough for the purpose intended, but any number of said elements can be used when the load on the shelf is excessive. In Figure 6, I have shown four of said elements and their relative arrangement for use. The slots 14

110

in the walls of the body 10, are preferably arranged in series, with the slots of each series slightly spaced apart in superimposed relation. By reason of this construction aligned slots of 5 opposed walls can be selectively used so that the shelf can be supported at different heights within the stand. Obviously this permits of variation in the size of the merchandise receiving compartments defined by the space above and below the 10 shelf 12, as either end of the stand can be arranged uppermost for use.

I have illustrated in Figures 7 and 8 a modified form of the shelf supporting means, designed for use with the slots 14. In this form of the 15 invention I employ substantially U-shaped elements, each formed from a single piece of material, and including a head 17 from which project the spaced parallel limbs 18. These limbs are formed with aligned openings 19 adapted to 20 register with an opening 20 in the shelf 12, when the latter is received between the limbs 18. A headed pin 21 is then passed through these openings to hold the element 17 from becoming casually separated from the body 10. Manifestly 25 the elements 17 can be selectively inserted in the slots 14 to support the shelf 12 at any desired height, and can be quickly and conveniently removed from the body 10, when it is desired to collapse the structure.

30 While it is believed that from the foregoing description the nature and advantages of the invention will be readily apparent, I desire to have it understood that I do not limit myself to

what is herein shown and described, and that such changes may be resorted to as fall within the scope of what is claimed.

What is claimed is:

1. A collapsible display stand comprising a body portion having aligned slots in opposed walls, a separate shelf, positioned within said body portion, a plurality of separable shelf supporting elements received by said slots and arranged within the body portions, all of said elements traversing each other centrally beneath the shelf to effectively support the same, a stop flange on one end of each element to engage the adjacent wall, and the opposite end of said element being adapted to be bent parallel with and into engagement with its adjacent wall. 80

2. A collapsible display stand comprising a body portion of octagonal cross-sectional contour open at both ends and including walls connected by fold lines, whereby said body can be collapsed to provide a flat compact article, the opposed walls of the body having vertical series of aligned slots, a separate shelf snugly positioned within said body and contacting said walls, a plurality of flat elongated shelf supporting strips arranged within the body and in crossed relation and received by opposed slots, and a stop flange bent from one end of each strip to engage the adjacent wall of the stand, the other end of the strip being adapted to be bent parallel with the adjacent wall and into engagement therewith. 95
